ATTORNEY

UNITED STATES PATENT OFFICE.

IGNATIUS WASSERMAN, OF NEW YORK, N. Y.

COMBINED CATAMENIAL SACK AND ABDOMINAL SUPPORTER.

SPECIFICATION forming part of Letters Patent No. 267,956, dated November 21, 1882.

Application filed July 27, 1882. (No model.)

To all whom it may concern:

Be it known that I, IGNATIUS WASSERMAN, of the city, county, and State of New York, have invented certain new and useful Improvements in Catamenial Bandages, of which the following is a specification.

The object of this invention is to provide a catamenial device which, while combining the properties of lightness, elasticity, and detachability, shall be comfortable and convenient to the wearer.

The invention consists of a catamenial bandage, the body of which is composed of netting and provided with an elastic waist-strap at the top, elastic thigh-straps at the lower corners, a back-strap connecting the lower edge of the body at the center with the waistband, and a flexible absorbent-pad detachably connected to the lower part of the netted body.

In the accompanying drawings, Figure 1 represents my improved catamenial bandage in position for use. Fig. 2 is a perspective view of the same; and Figs. 3 and 4 are detail front view and a section of the absorbent-pad, showing its connection with the netted body.

Similar letters of reference indicate corresponding parts.

A in the drawings represents the main portion or body of my improved catamenial bandage, said body being composed of light open elastic netting, adapted to cover the abdomen and support the absorbent-pad B. The pad B is composed of wool, cotton, or other suitable absorbent material, and provided with a water-proof backing, which serves to protect the clothing of the wearer. An elastic waist-strap, C, is run through the top meshes or loops of the body A, and provided at its meeting ends with a suitable fastening device. Elastic thigh-straps D are attached to the lower

corners of the body A, the outer ends of said straps being also provided with fastening devices. A back-strap, E, extends from the lower edge of the netted body to the rear meeting ends of the waist-strap, to which it is buttoned or otherwise fastened. This back-strap passes between the thighs, and serves to hold the absorbent-pad in position. The absorbent-pad B is detachably fastened to the netted body by means of spring loop-pins or otherwise, and can be readily replaced by a fresh pad. A short central front strap, F, is connected at both ends to the netted body, and passes transversely across the pad, serving to strengthen the former and as a rest for the latter.

The weight of this bandage is evenly distributed. The bandage is open and of an elastic character, and contributes greatly to the comfort of the wearer.

I am aware that supporters of knitted material are well known; also supporters or bandages provided with a back-strap passing from the front part of the supporter, between the legs, to the back part of the same, and I therefore do not lay any claim to these features.

Having thus described my invention, I claim as new and desire to secure by Letters Patent—

The combination of an open elastic body, A, composed of netting, a waistband, C, at the top thereof, thigh-bands D at the lower corners, a back-strap, E, and a detachable absorbent-pad, B, substantially as set forth.

In testimony that I claim the foregoing as my invention I have signed my name in presence of two subscribing witnesses.

IGNATIUS WASSERMAN.
